HOSE REEL HOUSING FOR A FIRE TRUCK

Calvin S. Kunkle, Tipton, Ind., assignor to FMC
Corporation, San Jose, Calif., a corporation of
Delaware

Filed Sept. 4, 1968, Ser. No. 13,400

Term of patent 14 years

Int. Cl. D12—14

U.S. Cl. D14—6

FIG. 1

FIGURE 1 is a front left perspective view of a hose reel housing for a fire truck showing my new design;

FIGURE 2 is an enlarged front left perspective view thereof; and

FIGURE 3 is an enlarged rear right perspective view thereof.

The fire truck shown in broken lines is included for illustrative purposes only.

I claim:

The ornamental design for a hose reel housing for a fire truck, as shown and described.
